United States Patent Office.

JOHN DEWE, OF TORONTO, CANADA.

Letters Patent No. 95,204, dated September 28, 1869.

IMPROVEMENT IN SEAL-LOCKS FOR BAGS.

The Schedule referred to in these Letters Patent and making part of the same.

To all whom it may concern:

Be it known that I, JOHN DEWE, of the city of Toronto, in the county of York, Province of Ontario, Canada, have invented a new and useful Improvement in Seal-locks; and I do hereby declare that the following is a full, clear, and exact description of the construction and operation of the same, reference being had to the annexed drawings, making a part of this specification, in which—

Figure 1 is an elevation and plan, partially sectional, of rivet-lock;

Figure 2, a flat and edge view of strap, showing the position of lock;

Figure 3, view of bag, with strap and lock attached;

Figure 4, view of mouth of bag, with leather binding;

Figure 5, details of the bolt;

Figure 6, section, showing the strap locked; and

Figure 7, plan of strap, as applied to mail-bag.

My invention consists of a plate, having a tube extending through it, at or near its centre, perpendicular to its plane, and having arranged within it one or more catches, which serve, in conjunction with a rivet of lead, or other similar material, to form a seal-lock for mail and other bags, as hereinafter fully explained.

To enable others skilled in the art to make and use my invention, I will proceed to describe its construction and operation.

In the drawings—

A indicates a bag, having a cord, leather strap, hem, or other suitable binding, G, around its mouth; B is a strap, provided at one end with a tongueless buckle or loop, C, and toward the other end with a series of holes, F F F; and between the buckle and holes a lock, E, constructed as shown in fig. 1, and attached as shown in fig. 2; and I is a rivet or bolt, employed in connection with the lock, as hereinafter described.

The lock E is composed of a plate, e, having a tube, e', extending through it at its centre, perpendicular to its plane.

Within the plate e are one, two, or more snap-catches, m m, bevelled at their adjacent ends, and projecting into the tube, springs n n being employed to force them forward.

The rivet I is adapted to be thrust down into tube e' until, just as its head rests on the end of the tube, the catches m m spring into notches H H on the side of it, and prevent it from being withdrawn until the

head is broken off. It is made smaller at the neck than elsewhere, so that the head can be cut or broken off without difficulty, and that any attempt to remove the rivet will result in the detachment of the head. Its head may be stamped or marked with any numbers, letters, or seal desirable for any particular purpose.

The material of the rivet is lead, tin, zinc, pewter, type-metal, or other suitable metal or material.

Thus constructed, the strap is placed around the neck of the bag. Its loose end is passed through the tongueless buckle or loop C. It is then turned backward and tightened, so that the tube e will project through one of the holes F, as shown in fig. 6. The rivet I is then inserted into the tube, and pressed down till its head rests upon the end of the tube and upon the surface of the strap, in which position the catches snap into the notches H H, and confine the rivet in the tube, so that it cannot be removed until its head is broken off.

A tag or label, D, may be attached to the strap before it is fastened in the manner above described, for any purpose required.

The rivets I I are made in any quantity required, and are differently stamped and marked, so that they cannot be easily duplicated.

The marks, stamps, or seals may not only be placed upon their head, but upon their sides, ends, or elsewhere.

When used by the post-office department, a number or numbers may be added, showing where the bag has been made up and sealed.

I am aware that a locking-bolt, having arranged, within an opening in its pointed end, two spring-catches, in connection with which a steel key, resembling my rivet in form, is intended to be used, has been invented by another; and I therefore wish it to be understood that I make no claim to such invention; but having thus described my invention,

What I claim as new, and desire to secure by Letters Patent, is—

A lock, consisting of the part E, having the tube e', plate e, and snaps m m, in combination with the rivet I, having a stem, head, fragile neck, and side notches H H, and strap B, substantially as and for the purposes herein specified.

JOHN DEWE.
